SAFETY FEED DEVICE

Ellsworth B. Riley, Philadelphia, Pa.

Application July 8, 1942, Serial No. 450,179

2 Claims. (Cl. 192—127)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a safety feed device for a press and is particularly applicable to a punch press in which a series of operations are performed on a strip of material after which the strip is cut into a series of small units.

Many articles such as the circular plates of a mechanical time fuse are made from a strip of material in a progressive die. In this type of machine the material is fed in at one end and a series of different punching and shaving operations are performed on the strip, the last step being to cut the strip into units, forming the round plates. The dies in such a press are very expensive, so that it is important to avoid injuring them. If the strip is not moved approximately the proper distance forward in each step the dies may be brought down on solid metal. Since some of the dies are designed only for shaving, the contact of such a die with the solid strip results in injury.

One of the first operations performed on the strip is the punching of a hole which is used as a centering hole in the subsequent operations. However, this will take care of only minor variations in feed and will not correct the gross errors which result in damage.

It is therefore the object of the present invention to provide a safety feed for presses which will make it substantially impossible to harm a die because of a mis-feed. Other objects will be apparent on reading the specification.

In general, the above object is achieved by providing an arm or detent which contacts the work and which prevents the operation of the press unless the work is correctly centered.

In the drawing, Figure 1 represents, in plan, the base, feed way and a work piece of a multiple acting press with the present invention in place. The dies which reciprocate over the feed way have been removed. Figure 2 represents the controls of a hand fed press showing one manner of utilizing the present invention in conjunction with such a control.

Referring to the drawing by reference characters, the bed 1 of a press is provided with a feed way 2 for receiving a work piece. A strip 3 of metal 3 is fed into the feed way where it is acted upon by a series of dies. A stop 4 at one end of the bed and shoulders 5 on the feed way prevent the strip from being thrust too far between strokes of the die. However, there is

nothing which insures that the strip is fed completely up to the proper position, or to prevent its slipping back when it does get to the proper place. To remedy this situation a sliding arm or 5 detent 6 is provided which slides in a slot cut in the feed way. Arm 6 is forced into contact with the work piece by means of a spring 7 acting against a stop 8 which is fastened to the bed of the press. Arm 6 is set at such an angle that it yields when material is pushed into the feed-way, but will not allow the material to be withdrawn. The outer end of arm 6 is provided with a projection 9 which comes in contact with and 10 closes a switch 10 when the arm is fully drawn into the feed slot. Switch 10 is of the normally open type. When the arm is partially or fully withdrawn from the slot switch 10 is opened.

In Figure 2 there is shown the treadle operated control of the die. When foot pedal 11 is depressed, valve 12 is opened allowing compressed air to enter cylinder 13 from a source not shown. This causes control rod 14 to move downward, engaging the clutch (not shown) which operates the die. A small arm 15 is provided on rod 14 20 and directly under arm 15 a pivoted catch 16 of ferromagnetic material is placed. This catch is normally held in engagement with arm 15 by means of a spring 17. An electromagnet 18 is suspended in proximity to catch 16 so that when 25 the electromagnet is energized catch 16 is drawn out of contact from arm 15. Thus, when the electromagnet is energized rod 14 is free to move and to operate the clutch bringing down the dies but if the electromagnet is not energized the 30 clutch is locked so that the operator cannot bring down the dies. In operation, a suitable source of current is provided to energize the electromagnet and switch 10 is connected so that it closes the 35 circuit.

40 This invention has been described in connection with a pneumatically actuated manual press, but it is apparent that the exact method of connecting the control illustrated need not be used. Similarly, the invention is not limited to devices on which only punching and shaving operations 45 are performed but is applicable to other devices as well, such as multiple acting drawn presses.

I claim:

1. In combination with a punch-press, a longitudinal guideway for a strip of stock to be operated upon, a stop to limit the forward longitudinal movement of the stock through said guideway, a slidable detent spring-urged obliquely into said guideway into the path of movement of the work in entering it in said guideway wherein it is

adapted to engage a sheared portion of the stock to prevent retrogressive movement of said stock, and electromagnetic means operated by said detent only when the detent is in engagement with the stock to allow further press operations.

2. In combination with a punch press, stock to be progressively operated upon by the punch press, a stop to limit the forward longitudinal

5 motion of the stock, a sliding detent to tangentially engage a sheared portion of the stock to prevent retrogressive movement and an electromagnetic unlocking detent actuated by the sliding detent to permit press operation only on full engagement of the sliding detent with a sheared portion of the stock.

ELLSWORTH B. RILEY.
